[57] CLAIM

The ornamental design for a fuel dispenser, as shown and described.

DESCRIPTION

FIG. 1 is a front elevational view of a fuel dispenser showing our new design, the rear being substantially plain and unornamented;

FIG. 2 is a top plan view thereof, portions of the hose being shown in broken lines for ease of illustration;

FIG. 3 is a right side elevational view thereof;

FIG. 4 is a left side elevational view thereof;

FIG. 5 is a front elevational view of another embodiment of our new design of FIGS. 1-4 wherein the rear view is identical thereto;

FIG. 6 is a top plan view thereof, portions of the hose being shown in broken lines for ease of illustration;

FIG. 7 is a right side elevational view thereof, the left side being identical thereto;

FIG. 8 is a front elevational view of another embodiment of our new design of FIGS. 1-4, the rear being substantially plain and unornamented;

FIG. 9 is a top plan view thereof, portions of the hoses being shown in broken lines for ease of illustration;

FIG. 10 is a right side elevational view thereof, the left side being a mirror image thereto.
